OF NEW JERSEY.

THROTTLE VALVE FOR ROCK DRILLS.

Application filed May 28, 1925. Serial No. 33,321.

To all whom it may concern:

Be it known that we, LEWIS C. BAYLES and FRED M. SLATER, citizens of the United States, and residents of Easton, in the county of Northampton and State of Pennsylvania, have invented a certain Throttle Valve for Rock Drills, of which the following is a specification accompanied by drawings.

0 This invention relates to throttle valves, but more particularly to throttle valves used in rock drills for controlling the admission of pressure fluid.

One object of the invention is to prevent 5 accidental turning of the throttle valve.

Another object is to enable the throttle valve to be held by mechanical means in limiting and intermediate positions.

Other objects will appear hereinafter.

10 The invention consists of the combination of elements, features of construction and arrangement of parts having the general mode of operation substantially as hereinafter described and more particularly 15 pointed out in the appended claims and illustrated in the accompanying drawings, in which—

Figure 1 is a sectional view in elevation of a head block for a rock drill provided 10 with a throttle valve constructed in accordance with the practice of the invention.

Figure 2 is a transverse sectional view taken through Figure 1 on the line 2—2 looking in the direction of the arrows,

15 Figure 3 is a perspective view of a throttle ratchet, and

Figure 4 is a perspective view of a throttle ratchet ring.

Referring to the drawing, the invention 10 is shown embodied in a rock drill of which only a head block A is shown to illustrate the invention. In this instance, a valve chamber B which is preferably of cylindrical formation extends transversely 15 through the head block and a recess C is formed coaxially with the valve chamber in one side of the head block. Disposed within the chamber B is a throttle valve D having a recess E in one end. Motive fluid is admitted to the recess E of the throttle valve through a suitable connection F which is held in position by a nut G

screwed into one side of the valve chamber B. In this instance, a supply passage H is formed in the head block for supplying pressure fluid to the percussive cylinder (not shown) and is adapted to communicate with the recess E of the throttle valve through a port J formed in the wall of the valve. A passage K leading from the valve chamber provides communication between the recess E of the valve and a feed cylinder (not shown) through a passage L formed through the valve near the inner end of said recess. The port J and the passage L of the valve are so arranged with respect to each other that they may be simultaneously brought to register with the passages H and K respectively.

In this instance, the valve D is provided 70 with a stem O of smaller cross sectional area thus forming the shoulder P at the juncture of the valve and said stem. A bore Q is formed between the valve chamber B and the recess C and provides a bearing for the stem O. The outer end R of the stem O is preferably of polygonal cross sectional area to receive a throttle lever S, and the throttle lever S is held against removal from said stem by a pin T. 80

In accordance with the present invention, a ratchet ring U is arranged on the stem O to engage the polygonal portion R of the valve stem adjacent the handle S, and is provided on its inner surface with 85 a pair of diametrically opposed extensions V on which are formed teeth W. A ratchet X is arranged slidably upon the stem O and carries a pair of diametrically opposed lugs X' on its periphery to extend 90 slidably into grooves Y formed in the recess C. On one face of the ratchet X are formed teeth Z to cooperate with the teeth W on the ratchet ring U. The teeth Z are in this instance formed in series in opposed 95 arcs to permit the valve to be rotated through a quadrant. A pair of opposed stops b are formed on the face carrying the teeth Z and cooperate with the extensions V for limiting rotation of the valve. In order to hold the teeth Z on the ratchet 100 in yieldable engagement with the teeth W of the ring thus preventing accidental turning of the valve, a spring c is arranged

about the stem O and bears with one end against said ratchet and with the other end against the end wall of the recess C.

To prevent the accumulation of dust within the recess C, a passage d is formed through the valve D and extends through the stem O to communicate at its outer end with the recess C. The passage d is so positioned with respect to the passage K in the head block that when the valve is in closed position, the passage d will register with the passage K and provide a means of escape for the pressure fluid in the feed cylinder. The pressure fluid thus escaping from said cylinder is exhausted into the recess C and will remove any dust which may have accumulated in said recess.

The advantages of the present invention reside in the fact that the throttle valve D may be held against accidental turning in both opened and closed position as well as intermediate positions, and in the manner in which the parts forming the locking element are protected against the abrading action of dust which ordinarily causes excessive wear and shortens the life of these parts. A further advantage resides in the fact that by this arrangement a cylindrical valve may be used, and that the tendency of the valve to stick within the valve chamber may thus be eliminated. A perfect seal may be obtained at all times since the valve is constantly exposed to live pressure which forces the shoulder P of the valve against the end of the chamber B thus preventing the building up of pressure between said shoulder and said end wall. An additional advantage is that when the air is shut off from the valve, the valve will still be held tightly on its seat by the spring c.

The above described valve together with its locking or holding mechanism has been found to be efficient in operation, it is inexpensive to manufacture and due to the cleansing action of the pressure fluid permitted to escape into the recess C, the parts will be capable of rendering service for a longer period of time as compared with machines unprovided with this feature.

We claim:

1. In a throttle valve for rock drills, the combination of a head block, a valve in said head block, a stem carried by said valve, a ratchet ring on said stem, a ratchet on the stem and cooperating with the ratchet ring and the head block for

holding the valve in located position, and means on the ratchet and ring to limit rotative movement of the valve.

2. In a throttle valve for rock drills, the combination of a head block, a valve in said head block, a stem carried by said valve, a ratchet ring on said stem to rotate therewith, teeth on said ring, a hollow ratchet slidable on said stem, lugs on the ratchet to hold said ratchet against rotation, grooves in the ratchet to receive the teeth on the ring, a spring to hold the teeth on the ring in engagement with the grooves in the ratchet for holding the valve in limiting and intermediate positions, and means on the ratchet for limiting rotative movement of the valve.

3. In a throttle valve for rock drills, the combination of a head block having a cylindrical chamber and a recess, grooves in said recess, a valve in said chamber carrying a stem, a ratchet ring on the stem, a pair of teeth on said ring, a hollow ratchet slidable on said stem and having a pair of lugs to cooperate with the grooves in the head block to prevent rotation of the ratchet, teeth formed on the ratchet to cooperate with the teeth on the ring for holding the valve in intermediate positions, a spring to hold the teeth on the ratchet ring and the ring in yieldable engagement, and means for limiting rotative movement of the valve.

4. In a throttle valve for rock drills, the combination of a head block having a cylindrical chamber and a recess, grooves in said recess, a valve in said chamber, a stem carried by said valve, a handle on said stem for rotating the valve, a ratchet ring on the stem adjacent the handle, said ratchet ring being adapted to engage the handle to rotate therewith, a pair of diametrically opposed teeth on the ring, a ratchet arranged slidably on the stem and having a pair of diametrically opposed lugs to register with said grooves for holding the ratchet against rotation, teeth on the ratchet to cooperate with the teeth on the ring for holding the valve in located position, a spring on said stem for holding the teeth on the ratchet and the ring in yieldable engagement, and stops on the ring and ratchet for limiting rotary movement of the valve.

In testimony whereof we have signed this specification.

LEWIS C. BAYLES.
FRED M. SLATER.
